CONTAINER COVER

Charles T. Walter, Chicago, Ill., assignor to Industrial Patents Corporation, Chicago, Ill., a corporation of Delaware

Application May 29, 1936, Serial No. 82,434

2 Claims. (Cl. 229—5.7)

This invention relates to an improved container cover.

One of the objects of the invention is to provide an improved fibrous container provided with a metal ferrule.

Another object of the invention is to provide an improved fibrous container end provided with a metal ferrule for a fibrous container.

Other objects will be apparent from the description and claims which follow.

It has been proposed to produce containers having tubular fibrous body walls and fibrous metal ends joined by a welded metallic ring loosely associated with a cupped fiber disk. Such container ends cannot be handled readily with standard can closing machines. In standard can closing machines, the ends for the containers are fed from a stack and handled primarily by the flange. It is a difficult, tedious procedure to assemble three units, a can body, a metal ring and a fibrous end at one time. The preferable procedure is to handle the preformed end as one unit and the container body as another unit.

The present invention provides a container cover composed of a single unit comprising a fiber disk and a metallic ring which may be conveniently handled in standard can closing machinery.

In the drawing, similar reference characters in the several figures indicate similar parts.

Figure 1 is a fragmentary view, partly in section, of a fiber disk to which a metal ring has been affixed.

Figure 2 is a fragmentary view, partly in section, of a container employing the cover shown in Figure 1.

Figure 3 is a fragmentary perspective view of the container shown in Figure 2.

The container cover comprises fibrous disk 14 provided with peripheral flange 15. Ring 16, of tin plate or other suitable material, is bent and flanged into the cross section shown in Figure 1. I will be noted from this cross section that metal ring 16 has been bent to form a U-shaped flange 17 by bends 18 and 19, the cupped portion 15 of disk 14 being held firmly in U-shaped flange 17. An outer radial flange 20 is formed by bending

the rim portion of the ring as at 21 and 22. The ring may be welded or not as desired. An unwelded condition is shown as at 24. Container cover 23 may be affixed to the body walls of a container in the manner shown in Figure 2, wherein it will be seen that flange 20 is crimped to the end edge 12 of body wall 13 by a standard seaming machine forming the standard crimp 25.

More specifically, the metal ring 16 comprises a circular radial flange 20 provided at its inner edge with a substantially U-shaped member 17, the cross member of the U-shaped member 17 being extended in substantially the same plane as the radial flange 20.

It will be seen that the present invention contemplates a combination fiber disk and metal ferrule container cover which may be handled as an integral unit in which one edge of a metal ring is affixed to the edge of a fiber disk.

I claim:

1. A unit container cover comprising a fibrous disk provided with a peripheral flange and a metal ring for securing the cover within a fibrous container body with the peripheral flange extended outwardly toward the end edge of the container body comprising a circular radial flange provided at its inner edge with a U-shaped member crimped over the peripheral flange, the radial flange being adapted for crimping to the outer wall of the fibrous body, the cross member of the U-shaped member being extended in substantially the same plane as the radial flange.

2. In a container including a tubular fibrous body and an end member comprising a fibrous disk provided with a peripheral flange, a metal ring for securing the end within the tubular body with the peripheral flange extended outwardly toward the end edge of the tubular body comprising a circular radial flange provided at its inner edge with a U-shaped member, the cross member of the U-shaped member being extended in substantially the same plane as the radial flange, the U-shaped member being adapted to be crimped around the peripheral flange of the end and the radial flange being adapted to be crimped against the outer wall of the tubular fibrous body.

CHARLES T. WALTER.
